W. Hiley,
Sash Balance.
No 22,954. Patented Feb. 15, 1859.

UNITED STATES PATENT OFFICE.

WILLIAM HUEY, OF CHRISTIANA, PENNSYLVANIA.

ELEVATOR FOR WINDOW-SASHES.

Specification of Letters Patent No. 22,954, dated February 15, 1859.

To all whom it may concern:

Be it known that I, WILLIAM HUEY, of Christiana, in the county of Lancaster and State of Pennsylvania, have invented a new and useful Elevating Attachment to be Applied to Window Sashes; and I do hereby declare that the following is a full, clear, and exact description of the same, reference being had to the annexed drawings, making 10 a part of this specification, in which—

Figure 1, is a vertical central section of a window with my invention applied to it. x, x , Fig. 2, indicates the plane of section. Fig. 2, is also a vertical section of ditto, 15 taken in the line x', x' Fig. 1.

Similar letters of reference indicate corresponding parts in the two figures.

The invention is designed to facilitate the raising and lowering of the sashes and supersede weights and similar appliances that have been previously used for the same purpose.

To enable those skilled in the art to fully understand and construct my invention I 25 will proceed to describe it.

A, represents a window frame or casing in which two sashes B, C, are placed as usual and allowed to slide freely up and down therein. In each side of the frame or 30 casing A there are placed four pulleys a , two for each sash, each sash having the pulleys at each side of it, see Fig. 2, in which the pulleys of the lower sash C, are all shown. To the lower part of each side of each sash 35 a cord b , is attached. These cords pass over the upper pulleys a , of the sashes and then pass downward under the lower pulleys a , and over drums c, c' , the two cords of each sash passing over the drums which are 40 placed loosely on a shaft D, in the lower part of the frame or casing. The shaft D passes transversely through the frame or casing A, and has a pin d , passing transversely through it. This pin is fitted or 45 placed in a chamber d' , formed by having a recess in the inner ends of each drum and is made to connect with either drum by means of pins e , which are driven into the ends of the drums, the shaft D being allowed 50 to move in its bearings so as to permit the pin d , to be coupled with either drum. This will be clearly understood by referring to Fig. 1. Each drum c, c' , has a ratchet d'' , formed on it in which spring or elastic hold-

ing pawls f , catch. These pawls are fitted in 55 the lower part of the frame or casing, as shown more particularly in Fig. 1.

E, E, are bent rods the lower ends of which are fitted loosely on a rod or shaft g , in the frame or casing, the upper parts of 60 the rods passing through the sill piece h , of the frame and having each a button i , fitted on their top ends. The rods E, bear or rest on the pawls f , or are directly over them, so that the pawls may, when desired, 65 be freed from their respective ratchets d'' , by depressing the rods E, E.

The cord b , of the lower sash C is attached to the drum c , and the cord of the upper sash B, is attached to the drum c' , as 70 shown clearly in Fig. 1.

The inner end of the shaft D, that is to say, the end within the apartment has a crank j , attached to it.

The operation will be readily seen. If 75 the shaft D be pulled inward toward the operator the pin d , of the shaft D will engage with the pins e , of the drum c , and if the shaft D be turned from left to right the cords b , of the sash C, will be wound on the 80 drum c , and the sash G consequently raised. The sash will be retained at any height within the range of its movement by means of the pawl of the drum c , catching into the ratchet of said drum. If the operator shoves 85 the shaft D, from him the pin d , will engage with the pins e , of the drum c' , and by turning the shaft D, in the same direction as before the sash B, if down, will be raised, the pawl f , of the drum c' cutting 90 into the ratchet on said drum. Either sash may be lowered by depressing the rod E, which will throw the pawl f , out from the 95 table of the ratchet which is in the drum to which the cords of the sash to be lowered is attached. The sash being prevented by falling too rapidly in consequence of the operator having his hand on the crank j , and restraining its motion.

By this invention it will be seen that the 100 sashes may be raised and lowered with facility. If either sash should happen to "stick" or adhere in the casing a considerable power without material exertion may be applied to raise it. There are no parts 105 that are liable to become inoperative.

The device is simple, efficient, may be readily and economically constructed.

I would remark that the insect screen F may be operated in the same way as the sashes.

Having thus described my invention what 5 I claim as new and desire to secure by Letters Patent, is—

The arrangement and combination of the rods E, E, pawls (f), ratchets (d''), loose

drums (c, c') sliding shaft D, pins (d, e), and cords (b b), as and for the purpose 10 herein shown and described.

WILLIAM HUEY.
